UNITED STATES PATENT OFFICE.

ANDREW B. HENDRYX, OF ANSONIA, CONNECTICUT, ASSIGNOR TO
HENDRYX & BARTHOLOMEW, OF SAME PLACE.

IMPROVEMENT IN FEED-CUPS FOR BIRD-CAGES.

Specification forming part of Letters Patent No. **156,348**, dated October 27, 1874; application filed
August 28, 1874.

To all whom it may concern:

Be it known that I, ANDREW B. HENDRYX, of Ansonia, in the county of New Haven and State of Connecticut, have invented a new Improvement in Feeding-Cups for Bird-Cages; and I do hereby declare the following, when taken in connection with the accompanying drawings and the letters of reference marked thereon, to be a full, clear, and exact description of the same, and which said drawings constitute part of this specification, and represent, in—

Figure 1, a perspective view; and in Fig. 2 a top view, showing the method of attaching the cup.

This invention relates to an improvement in the cups used for feeding birds in cages, the object being to attach the cup without moving or opening any part of the cage; and it consists in a cup with a spout extending from one side and widening slightly from the cup, so that the spout may be forced between the wires, and the elasticity of the wires will cause them to return into the contracted portion of the cup and hold the cup in place.

A is the principal part of the cup, which may be of any desirable form, and from one side of which projects the feeding-spout B, preferably made by turning that side of the cup outward to the full depth of the cup, as seen in Fig. 1. This spout increases in width directly from the cup for a short distance, so as to form a recess, *a*, on each side.

The cup is applied by forcing the spout between the wires, the wires here represented in solid black, as at *d*, in their natural position. The wires yield to allow the enlarged portion of the spout to pass through and then return into the recesses *a* and grasp the cup with sufficient force to hold it in place, as seen in Fig. 2.

I claim as my invention—

The herein-described feeding-cup for bird-cages, consisting of the cup A and spout B, and with recesses *a*, by means of which to secure the cup to the cage between the vertical wires, substantially as set forth.

ANDREW B. HENDRYX.
